UNITED STATES PATENT OFFICE.

CHARLES BALLARD HALE, OF PARK RIDGE, ILLINOIS, ASSIGNOR TO TIME-SYSTEMS CO.,
OF DETROIT, MICHIGAN, A CORPORATION OF MICHIGAN.

PRESSURE-GAGE.

1,330,466.

Specification of Letters Patent.

Patented Feb. 10, 1920.

Application filed May 20, 1916. Serial No. 98,765.

To all whom it may concern:

Be it known that I, CHARLES BALLARD HALE, a citizen of the United States, residing at Park Ridge, in the county of Cook 5 and State of Illinois, have invented certain new and useful Improvements in Pressure-Gages, of which the following is a specification.

This invention relates to new and useful 10 improvements in pressure gages and has for its object the construction of a gage which will measure the pressure of impulses of air passed through a line pipe and which may be readily shipped attached to its coöperating 15 apparatus without being damaged or broken.

With the above and other objects in view, as will be apparent, this invention consists in the construction, combination and arrangement of parts all as hereinafter more 20 fully described, claimed and illustrated in the accompanying drawing wherein:—

Figure 1 is a front elevation of a gage constructed in accordance with the present invention;

Fig. 2 is a central vertical section taken along line 2—2 of Fig. 1;

Fig. 3 is a similar view taken along line 3—3 of Fig. 2;

Fig. 4 is a horizontal section taken along line 4—4 of Fig. 1, and

Fig. 5 is likewise a horizontal section taken along line 5—5 of Fig. 1.

In carrying out the present invention, a 35 tubular shell or casing is provided having an elongated sight opening therein. A head is inserted in the upper end of the shell or casing and has sockets therein in which are received the ends of a U tube; one of said 40 sockets connecting with the atmosphere while the other communicates with the source of pressure. Within the U tube is a column of colored liquid, in each of the branches thereof, which balance when 45 atmospheric pressure prevails in both branches; but which becomes unbalanced when an impulse of pressure or a constant pressure emanates from the source thereof, causing the column of liquid in the branch 50 communicating with the atmosphere to rise while the other column becomes lower.

Referring more particularly to the drawing 10 designates a shell or casing, tubular in its formation, and cut away to form the 55 elongated sight opening 11, through the me-

dium of which the gage may be read. In producing the casing or shell 10 the stock from which it is formed, cut or otherwise taken, is so cut that a heavy inwardly extending bur 12 is formed at one end of said 60 shell or casing, the utility of which will be hereinafter apparent.

Oppositely disposed to the end of the shell or casing 10 having the bur 12, is a head 13, fitted snugly but removably in the coöperating end of said shell or casing and having an outstanding, faced shoulder 14 formed thereon, which rests upon the upper end of the shell or casing when the head is located therein. A nipple 15 projects centrally 70 from the head 13, and constitutes the connection between the pipe 16 and the gage. The head 13 is held within the end of the shell or casing 10 by means of screws 17 passing through openings in said shell or 75 casing and threaded into the head 13, as illustrated in Fig. 2.

The inner end of the head 13 has a pair of independent sockets, 18 and 19, respectively, formed therein, for the reception of the ends 80 of the branches 20^a and 20^b of the U tube 20, said ends being sealed or anchored in the said sockets by a plastic compound of litharge and glycerin being allowed to set around said ends against the inner terminal of the 85 head 13 as at 21. It is of course understood that other sealing compounds may be readily used without departing from the spirit and scope hereof. The socket 18, in which is seated the end of the branch 20^a, of the U 90 tube 20 terminates in a passage 22, leading to and communicating with the nipple 15; while the socket 19, in which is seated the branch 20^b of the U tube 20, terminates in the transverse passage 23 which extends to 95 the exterior of the shoulder 14 of the head 13. Hence it becomes manifest that one branch (20^a) of the U tube 20 is connected to the pipe 16 while the other branch (20^b) communicates with the atmosphere: and by 100 this method any pressure, other than atmospheric pressure, within the pipe 16 will also be transmitted to the U tube 20.

For the purpose of indicating such pressure, the U tube is partially filled with any 105 suitable colored liquid whereby a column of said liquid is located in each branch 20^a and 20^b thereof. When conditions are such that atmospheric pressure prevails in the pipe 16 the columns of liquid in the branches 20^a 110

and 20^b balance, or maintain the same level, as is illustrated in the various views of the drawing. If, however, pressure exists in pipe 16 the columns of liquid will assume 5 different levels *i. e.* the column in the branch 20^b rising while the column in the branch 20^a becomes lower. Sub-atmospheric conditions in the pipe 16 cause a reversal of the levels of the columns of liquid in that the 10 column in the branch 20^a rises while the other column in the branch 20^b seeks a lower level.

The bend of the **U** tube 20 is embedded in the cotton or other like material 24, to prevent 15 damage to this tube, the material 24 absorbing all shocks, jars, etc., which otherwise would be damaging to the tube 20. This cotton 24 is held in place by the plaster of Paris or similar substance 25 set in the 20 burred end of the shell or casing 10. As the bur 12 becomes embedded in the plaster of Paris 25, it holds the same in place as well as forms a protection therefor.

What is claimed is:

25 1. In a pressure gage, the combination with a casing, of a head secured in one end thereof provided with a plurality of parallel sockets in its inner end, one of said sockets being connected to the exterior of said 30 head by means of a lateral passage communicating with the inner end of said socket, a nipple on the outer end of said head connected by a passage with the other of said sockets, a **U**-tube having the free terminals 35 of its arms mounted within the sockets aforesaid, an inwardly extending bur at the opposite end of said casing, a fabricated packing surrounding the bend in said tube, and a plastic material sealing the end of the tube 40 having the bur, said bur being embedded in said plastic material.

2. The combination with a shell or casing having a sight opening therein, of a single continuous **U**-tube so mounted in said casing that both arms thereof are visible through 45 said sight opening, a head in one end of said casing, having a pair of sockets therein, one for the reception of the free end of one arm of said **U** tube, and a lateral passage therein forming a means of communication 50 between one of said sockets and the atmosphere, a nipple carried by said head and communicating with the remaining socket for connecting it to a source of pressure, an inwardly extending bur formed from said shell or casing at the end thereof adjoining the elbow in the **U** tube, and a seal held in said shell or casing by the bur aforesaid.

3. The combination with a shell or casing having a sight opening therein, of a single 60 continuous **U**-tube so mounted in said casing that both arms thereof are visible through said sight opening, a head in one end of said casing, having a pair of sockets therein, one for the reception of the free end of one 65 arm of said **U**-tube, and a lateral passage therein forming a means of communication between one of said sockets and the atmosphere, a nipple carried by said head and communicating with the remaining socket 70 for connecting it to a source of pressure, an inwardly extending bur formed from said shell or casing at the end thereof adjoining the elbow in the **U**-tube, a seal normally flush with the end of the casing and having 75 said bur embedded therein, and liquid in said **U**-tube forming a column in each arm thereof, said columns being normally balanced until the admission of pressure to one arm of the **U**-tube through the nipple 80 aforesaid.

CHARLES BALLARD HALE.
